WELL FORMATION PACKER ASSEMBLY FOR
MEASURING GAS-OIL RATIOS

Gerald D. Barton, Tulsa, Okla., assignor to Stanolind Oil and Gas Company, Tulsa, Okla., a corporation of Delaware

Application June 4, 1949, Serial No. 97,110

5 Claims. (Cl. 73—155)

1

The present invention relates to a novel type of well formation packer assembly. More particularly, it pertains to a novel packer assembly having by-pass and valving means suitable for use in wells such as, for example, oil wells in which the ratio of gas to liquids produced is quite high.

An object of my invention is to provide a packer capable of readily maintaining its original position of setting when employed in wells having a high gas to oil ratio. It is a further object of my invention to provide a packer suitable for use in wells having a high gas to oil ratio wherein the volume of gas escaping from the packed off zone of the producing formation across the packer can be measured as it passes through the latter. A still further object of my invention is to provide a packer capable of separating in a satisfactory manner oil from gas, both of which are being produced from the same restricted zone, by allowing the gas to escape from said zone through a conduit communicating with the zone above and the packed off zone immediately below the packer, the passageway being capable of opening and closing at a predetermined level of the liquid in the packed off zone.

Packing elements of the type contemplated by my invention are useful in carrying out various operations in the presence of high gas pressures in a well bore. For example, in identifying fluids and their respective rates of production in a restricted zone, such as are described and claimed in copending application U. S. S. N. 97,764, filed June 8, 1949, by Ralph E. Hartline and Joseph D. Eisler, the device of the present invention may be advantageously employed. According to the aforesaid copending application well fluids may be identified and the respective rates at which these fluids flow may be determined by placing a string of vertically spaced electrodes in a packed-off zone in the well bore. The rate of flow of oil or water is measured by following the movement of the oil-water interface in the zone defined by two packers. The total fluids produced in the particular zone investigated is computed by the aid of a flow meter located in the tubing connecting the packers and which measures only the product from said zone. Production, preferably at a constant rate, is commenced and the rate of rise or fall of the oil-salt water interface is determined by observing the time at which the interface passes the electrodes. If the well fluid in the test zone is principally salt water at the time of setting the packers, the oil-water interface is high in the zone, initially. The interface

then moves downward during the test period if oil production occurs, and its rate of fall establishes the oil production rate if the bore hole diameter is known. By determining the total production passing through the flow meter and subtracting the production rate of the oil, as determined above, the production rate of the salt water can be ascertained. Thus, in systems for identifying and determining production rates of well liquids by gravimetric collection between packers in a restricted zone of an oil well, there is placed a differential pressure across the top packer equal to the static head resulting from the difference in density between the original fluid in the packed off zone and the fluid being produced plus the differential pressure resulting from the flow of the produced fluid. When the fluid collected under the upper packer is crude oil, the resulting differential pressure is not excessive and the requirement that the packer confine the produced fluid against this differential pressure does not impose too great a limitation upon its operation. The requirements imposed upon the upper packer are, however, much more severe when gaseous products produced from the packed off area accumulate under the packer. The greater density difference results in a markedly higher packer load imposed by the differential pressure thus produced. The term "density" as used herein refers to the differential pressure exerted on the underneath side of packer 2 produced by the hydrostatic head of the column of oil standing in tubing 4 on the column of oil and gas in the packed off zone with which the oil in tubing 4 is in communication through a conventional entrance port. Owing to the presence of gas in the column of fluid confined by the packed off zone, the density of that column is less than the column of oil standing in the tubing. It is this difference in density of these respective columns that produces the above-mentioned differential pressure. The identification of the well fluids and the determination of their respective production rates also becomes more complex by the creation of the gas-oil and oil-water interfaces. The gas-oil interface cannot be identified by means of the usual conductivity measurement systems. Moreover, it is the relatively more valuable liquid volume whose production rate is generally desired to be ascertained. With apparatus previously employed for measuring the production rates of well fluids in a packed off zone, much difficulty has been encountered where high gas to oil ratios prevail. Under such conditions the gas pressure tends to build up until the upper

packer becomes dislodged from its original setting thereby allowing a mixture of gas and entrained oil to pass upwardly around the packer into the unrestricted zone of the well bore. Obviously, under circumstances such as these, it is impossible to measure accurately the oil production rate from the test zone.

In order to reduce the packer load to a minimum in wells having a high gas to oil ratio and to allow measurement of the more valuable oil, I have devised a packing unit assembly suitable for bypassing produced gas across the packer. Thus, my invention contemplates the utilization of a conduit in communication with the zone above the packer and the test zone immediately below the packer, said conduit being capable of opening and closing at a predetermined level of the liquid in the test zone. The opening and closing of the conduit may be effected by any of several known methods such as by the utilization of a liquid level responsive means, for example, a float actuated valve. Such valve remains in a closed position as the result of the buoyant force exerted on the float by the oil. The corresponding force exerted by the gas, however, is insufficient to maintain the valve closed and the gaseous products are accordingly vented through the packer into the unrestricted zone above the unit until the gas-oil interface rises to lift the float and close the valve. By employing a float valve, for example, of the "snap action" type in which a definite differential motion of the float is required between full open and completely closed positions, it is possible to obtain an approximate quantitative measurement of the vented gaseous products. A switch attached to the valve can then transmit a signal through the switch circuit to a suitable recording means whereby estimation can be made of the volume of produced gas.

A preferred embodiment of the packing unit of my invention may be described with more particularity by reference to the accompanying drawing in which a packer 2 is disposed about a well tubing 4 having mounted therein a passageway or conduit 6. A float actuated valve assembly is shown attached to the lower portion of conduit 6 provided with seat 8. The buoyant force of the liquid oil applied to float 10 attached to arm 12, which is hingedly mounted to well tubing 4 at 14, functions to close conduit 6 by means of valve stem 16. The corresponding force exerted by the gas is insufficient to maintain valve seat 8 in the "closed" position; and, as a result, gaseous products from the formation are vented into the well bore above packer 2 through port 18 of conduit 6. Gaseous products continue to be vented into the well bore until the gas-oil interface rises to lift float 10 bringing valve seat 8 and valve stem 16 again into sealing relationship. By knowing the volume of gas required to lower the liquid-gas interface so that the float valve stem 16 disengages seat 8, and by knowing the volume of gas remaining after said gas and liquid interface causes the float valve stem 16 to disengage seat 8, the gas production rate can be calculated. Thus, the number of times that the system opens and closes per minute can readily be observed on recording ammeter 20 which indicates completion and breaking of circuit 22 through electrical contacts 24 and 26. The length of time the circuit remains open and closed may be recorded on a suitable time-driven recording roll 28 by needle 30 actuated by recording ammeter 20. Uniform movement of roll 28 is accom-

plished by known means, such as clock mechanism 32.

When employing a packing element of the type contemplated by my invention in isolating an intermediate well bore zone, it is desirable to provide exhaust ports in the well tubing above and below the packed off zone in order that gas or oil produced in the unrestricted zones of the well bore can be withdrawn therefrom into the production string and thereby avoid undue stress on the packing units.

It is apparent that various modifications can be made in the above-described apparatus without departing from the scope of my invention. In general, it may be said that the apparatus herein set forth is applicable to the solution of problems created by the presence of excessive volumes of gas in a well bore wherein it is desired either to qualitatively separate gases from liquids or to measure the production rate of such gases.

What I claim is:

1. In a well packer assembly for handling gas in a packed off zone of a well bore producing oil and gas, the combination comprising a well tubing, a packing element disposed about said tubing, there being an open-ended conduit communicating with the zone above and with said packed off zone immediately below said packing element, and a liquid level responsive valve means attached to said tubing and adapted to close the end of said conduit communicating with said zone immediately below said packing element at a predetermined liquid level in said packed off zone.
2. In a well packer assembly for handling gas in a packed off zone of a well bore producing oil and gas, the combination comprising a well tubing, a packing element disposed about said tubing, there being an open-ended conduit in said tubing communicating with the zone above and with said packed off zone immediately below said packing element, and a float actuated valve means attached to said tubing and adapted to close the end of said conduit communicating with said zone immediately below said packing element at a predetermined liquid level in said packed off zone.
3. A packer assembly for handling gas in a packed off zone of a well bore producing oil and gas comprising a well tubing, a packing element disposed about said tubing, there being an open-ended conduit in said tubing communicating with the zone above and with said packed off zone immediately below said packing element, means including liquid level responsive valve means attached to said tubing and adapted to open and close the end of said conduit communicating with the zone immediately below said packing element at a predetermined liquid level in said packed off zone.
4. In a packer assembly for handling gas in a packed off zone of a well bore producing oil and gas, the combination comprising a well tubing, a packing element disposed about said tubing, there being an open-ended conduit in said tubing communicating with the zone above and with said packed off zone immediately below said packing element, a liquid level responsive valve means attached to said tubing and adapted to close the end of said conduit communicating with the zone immediately below said packing element at a predetermined liquid level in said packed off zone, 75 a circuit including a switch connected to and ac-

tuated by said valve means which closes said circuit simultaneously with the closing of said liquid level responsive valve means, and means for producing an indication of electrical current flow in said circuit.

5. In a packer assembly for handling gas in a packed off zone of a well bore producing oil and gas, the combination comprising a well tubing, a packing element disposed about said tubing, there being an open-ended conduit in said tubing communicating with the zone above and with said packed off zone immediately below said packing element, a float actuated valve means attached to said tubing and adapted to close at a predetermined liquid level in the packed off zone of a 15 well bore the end of said conduit communicating with the zone immediately below said packing element, a circuit including a switch connected

6
to and actuated by said valve means which closes said circuit simultaneously with the closing of said valve means, and means for producing an indication of electrical current flow in said circuit.
